UNITED STATES PATENT OFFICE.

THOMAS J. FRABER, OF WASHINGTON, DISTRICT OF COLUMBIA.

COMPOSITION LATH.

1,325,241:

Specification of Letters Patent. Patented Dec. 16, 1919.

Application filed August 16, 1918. Serial No. 250,198.

To all whom it may concern:

Be it known that I, THOMAS J. FRABER, a citizen of the United States, residing at Washington, in the District of Columbia, 5 have invented new and useful Improvements in Composition Laths, of which the following is a specification.

This invention relates to composition laths, the object in view being to produce a 10 practical, cheap and reliable lath used in the construction of buildings and particularly frame buildings or structures, the formation of the lath being such as to enable plaster or mortar to adhere firmly to the 15 exposed face thereof when applied by the usual appliances, the improved lath embodying means whereby a plurality of keys or bonds are formed by the plaster or mortar and firmly engaged in key ways or openings 20 in the body of the lath.

With the above and other objects in view, the invention consists in the construction, combination and arrangement of parts, as herein described, illustrated and claimed.

25 In the accompanying drawing:

Figure 1 is a fragmentary plan view of the improved composition lath.

Fig. 2 is a fragmentary cross section through the same.

30 Fig. 3 is a section similar to Fig. 2 showing a modification in the structure of the lath.

The improved lath has, as the essential features thereof, a backing sheet 1, a face sheet 2, an interposed filling or body 3 of plastic material, and a plurality of key ways or slots 4, as shown in the drawings. The sheets 1 and 2 may be of any suitable flexible material, such as paste-board or card 35 board and the filling or interposed body 3 may be composed of plaster of Paris, or some cement composition, such as will adhere firmly to the sheets 1 and 2 and serve to cement the same together. The thickness 40 of the filling 2 is such as to provide a complete lath of the necessary thickness, the thickness of the lath being governed by the

nature of the structural work in connection with which the lath is used.

In Fig. 2, the sheets 1 and 2 are shown as 50 flat and parallel to each other. In Fig. 3, a modified form of the lath is shown, the same employing a flat backing sheet 5, a corrugated face sheet 6 and a filling 7. The members 5, 6 and 7 may be formed with the 55 same material stated above in connection with the members 1, 2 and 3 and the corrugations 8 of the corrugated sheet 6 may extend either vertically or horizontally but preferably the latter, so as to more effectively support the mortar or plaster applied to the face sheet 6. The key ways or openings 4 are preferably elongated horizontally 60 in the form of slots as indicated in Fig. 1, so that they will better support the body of 65 the plaster applied to the face of the lath. Where the corrugated form of lath is employed, the key ways 4 will extend lengthwise of the valleys or depressed portions 70 of the corrugation or corrugations as indicated in Fig. 3, so that the keys which enter said key ways will project from the thicker portions of said body of mortar or plaster.

It will, of course, be understood that the laths may be manufactured in any desired 75 size as to length and width and they may also be of any desired thickness.

I claim:

1. A composition lath comprising a face sheet, a backing sheet, and an interposed 80 body of plaster, one of said sheets being corrugated and the corrugations being internally filled with said body of plaster.

2. A composition lath comprising a face sheet, a backing sheet, and an interposed 85 body of plaster, one of said sheets being corrugated and the corrugations being internally filled with said body of plaster, the lath as a whole being formed with key-receiving openings elongated in the direction 90 of length of said corrugations.

In testimony whereof I affix my signature.

THOMAS J. FRABER,
